UNITED STATES PATENT OFFICE.

SOLOMON C. SPRING, OF BRISTOL, ASSIGNOR TO THE E. N. WELCH MANUFACTURING COMPANY, OF FORESTVILLE, CONNECTICUT.

DESIGN FOR A PENDULUM.

SPECIFICATION forming part of Design No. 15,547, dated November 11, 1884.

Application filed August 21, 1884. Term of patent 14 years.

To all whom it may concern:

Be it known that I, SOLOMON C. SPRING, a citizen of the United States, residing at Bristol, in the county of Hartford and State of Connecticut, have invented and produced a new and original Design for a Pendulum, of which the following is a specification, reference being had to the accompanying drawings, forming part thereof.

10 Figure 1 is a front view of my newly-designed pendulum; and Fig. 2 is a front elevation of a portion thereof, with the panel differently ornamented.

15 *a* designates a plain circular band, the space inclosed by which is filled by a suitable ornamental rosette, *A*, which may be changed from time to time, as the essential features of my design relate to the parts which surround the central rosette, *A*, rather than to the rosette

20 itself. Just outside of the band *a* is a ring-shaped panel, *b*, the surface of which is ornamented by a series of radial depressions, as shown. This circular panel is inclosed by a band or frame, *c*, the contour of which consists, mainly, of circular lines, which form a scalloped or indented edge, and upon the sur-

face of this band there is a series of circular depressions, as shown. Projecting from the edge of some of the scallops on the edge of the band *c* there are disk-shaped projections. 30 Above and below the band *c*, and connected thereto by short bars, are segmental bands *B* and *C*, having a bordered panel on their front, with ornamental work in relief. In Fig. 1 the upper panel on the segmental band *B* is shown 35 as ornamented by the word "Eclipse;" but in some cases I propose to omit said word, or letters of any kind, and substitute ornamental work, as shown in Fig. 2. At the ends of the segmental bands *B* and *C* are trefoils, as shown, 40 and also small circular projections in harmony with those upon the edge of the band *c*. The design also has central ornaments at the upper and lower edges of the segmental bands *B* and *C*, as shown. 45

I claim—

The design for a pendulum, substantially as herein shown and described.

SOLOMON C. SPRING.
